UNITED STATES PATENT OFFICE.

EUGENIA C. CAMPBELL, OF SAN FRANCISCO, CALIFORNIA.

INSUFFLATOR.

SPECIFICATION forming part of Letters Patent No. 693,587, dated February 18, 1902.

Application filed November 11, 1901. Serial No. 81,924. (No model.)

To all whom it may concern:

Be it known that I, EUGENIA C. CAMPBELL, a citizen of the United States, residing at San Francisco, in the county of San Francisco, State 5 of California, have invented certain new and useful Improvements in Insufflators; and I do hereby declare the following to be a full, clear, and exact description of said invention, such as will enable others skilled in the art to which it appertains to make and use the same.

My invention has for its object the production of an insufflator of improved construction, by the operation of which dry medicinal remedies may be readily applied without recession of the powder consequent upon the inflation of the bulb after compression of the latter.

The nature of my invention will be readily comprehended, reference being had to the 20 following description, taken in connection with the accompanying drawings, in which—

Figure 1 is an elevation, partly in section, of an insufflator embodying my invention. Fig. 2 is a detail view of a measuring-stop- 25 per employed in connection with the instrument.

In the drawings, A designates a casing having a chamber a, to the lower end of which is connected by a rubber tube b an air-bulb 30 c. The chamber a receives in practice the medicine, which is in dry powdered form and introduced through an opening a' in the upper end of the chamber, the opening being closed by a stopper d, having a scoop-blade d',

by which the powder may be measured. The 35 casing has a side extension A', to the outer end of which is fitted a speculum-tube e. The extension has exteriorly a sealing-flange a². A passage a³ leads from the chamber a through the extension and connects with a blow-tube 40 f, which terminates short of the end of the speculum-tube.

a⁴ denotes an air-duct which connects at its inner end with an air-tube g, the end of the latter being contiguous to the end of the 45 blow-tube.

In practice the introduced powder is expelled through the tube f by compression of the bulb, and the partial vacuum created in the latter is filled by air supplied by the duct and tube g. In the inflation of the bulb, therefore, there is no recession or sucking back of the powder; but, on the contrary, the entire contents of the chamber are delivered and applied to the affected part. 55

I claim as my invention—

An insufflator having a chamber for the material, an air-bulb connected with the chamber, a blow-tube leading from the chamber, an air-tube for supplying air to the blow-tube 60 for the inflation of the bulb, and a speculum-tube inclosing the air and blow tubes.

In witness whereof I have hereunto set my hand this 4th day of November, 1901.

EUGENIA C. CAMPBELL.

In presence of—

DOUGLAS DYRENFORTH,
WM. W. SHANNON.
